UNITED STATES PATENT OFFICE.

LOUIS E. PULFER, OF LOS ANGELES, CALIFORNIA.

SPRING COVER.

Application filed March 31, 1923. Serial No. 628,993.

To all whom it may concern:

Be it known that I, LOUIS E. PULFER, a citizen of the United States, residing at Los Angeles, in the county of Los Angeles and 5 State of California, have invented new and useful Improvements in Spring Covers, of which the following is a specification.

My invention relates to a protective covering and lubricating device for springs, and 10 the main object thereof is to provide a device of this character including a metal sectional dust and dirt proof covering for a spring, comprising a plurality of detachably pivoted sections, and embodying lubricating means for supplying continuously a 15 graphited oil to the spring.

Other objects and advantages will appear hereinafter, and while I show and will describe a preferred form of construction, I 20 desire to be understood that I do not limit my invention to such preferred form, but that various changes and adaptations may be made therein without departing from the spirit of my invention as hereinafter 25 claimed.

Referring to the annexed drawing which forms a part of this specification;

Fig. 1 is a side view of my invention applied to a leaf spring.

30 Fig. 2 is a longitudinal sectional view of a portion of my invention.

Fig. 3 is a perspective view of one of the sections of my invention.

Fig. 4 is a cross sectional view of my 35 invention in pivoted relation taken on the line 4-4 of Fig. 1.

Fig. 5 is a view similar to Fig. 4 in the act of pivotal disengagement of two of the sections.

40 Figs. 6, 7 and 8 are fragmentary bottom plan views of my invention showing respectively three different forms of connecting elements.

My invention includes a metal covering 1, 45 an oil container 2, a capillary pad 3 and a lower closing plate 4. The casing 1 is composed of a plurality of successively telescoping sections 5. Each section is made of a single sheet of metal bent longitudinally 50 into square tapering tubular form, to enclose a portion of a leaf spring 6, the inturned lower longitudinal edges of the section being spaced a short distance apart leaving a split in the bottom of the section, and are 55 formed with depending longitudinal flanges 7 respectively, which flanges are detachably

connected by connecting elements 8 to hold the section closely around the spring and to limit the outward expansion of the section.

Each section except the outermost end section is provided near its outer end in its side walls with oppositely disposed pivot bearing openings 9. The rear ends of the side walls of each section, except the innermost end section, are rounded in the form of knuckles 60 10 from the center and outer side of which knuckles extend pivots 11. The rear end of each section, except the innermost end section, telescopes into an adjoining section and its pivots 11 are detachably expanded with 65 the side walls of said section into the pivot bearing openings 9 of said adjoining section, whereby the sections are detachably and telescopically pivoted together at their ends over the spring 6. The upper wall of 70 each section, except the innermost end section, is formed with an extension 12 which extends under the outer end of the upper wall of an adjoining section to form good joints between the upper walls of the connected sections, so that the oil from the pad 3, which is placed on top of the spring 6 under said upper walls, will not leak out 75 through said joints.

The outermost end section is provided in 80 its upper wall near its forward end with a threaded opening 13, in which is screwed the lower threaded end of the oil containers 2 which supplies oil to the lower outer end of the pad 3, which oil feeds up along the 85 pad its entire length by capillary action and lubricates the spring 6. The plate 4 rests under the spring 6 upon the lower walls of the cover sections 5 and closes the longitudinal space in the bottom of the sections between the flanges 7 thus enabling the cover 90 1 to enclose the spring completely. The connecting elements 8 may comprise links 95 as shown in Fig. 6 or they may comprise springs 16 or pins 17 as shown in Figs. 7 100 and 8 respectively.

The sections 5 may be pivotally and telescopically connected together by compressing the lower part of the side walls thereof 105 towards each other so that the rear ends of each section except the innermost end section, may be telescoped within the forward end of the adjoining sections and then by releasing said side wall so that they will expand outwardly and expand the pivots 11 110 into the pivot bearing openings 9.

Conversely said sections may be discon-

nected by compressing their side walls and withdrawing said pivots from said openings and then pulling the sections apart, as shown in Fig. 5 of the drawings.

5. What I claim is:

1. In a covering and lubricating device for springs, a plurality of resilient telescoping sections split longitudinally at their lower sides, said sections being provided 10 with pivot bearing openings in their side walls near their forward ends and with pivots on their side walls near their rear ends adapted to be expanded into said openings when said side walls are expanded, and 15 connecting elements for connecting the lower split edges of said sections to hold said sections close around the spring.
2. In a covering and lubricating device

for springs, a plurality of resilient telescoping sections, split longitudinally at their 20 lower sides, said sections being provided with pivot bearing openings in their side walls near their forward ends and with pivots on their side walls near their rear 25 ends adapted to be expanded into said openings when said side walls are expanded, connecting elements for connecting the lower split edges of said sections to hold said sections close around the spring, and a plate resting under the spring upon the lower 30 walls of said sections and closing the splits therein.

In witness that I claim the foregoing I have hereunto subscribed my name this 12th day of March, 1923.

LOUIS E. PULFER.
